[57] CLAIM

The ornamental design for a combined carrying case and battery pack for a cordless telephone set, as shown and described.

DESCRIPTION

FIG. 1 is a front elevational view of a combined carrying case and battery pack for a cordless telephone set, as shown in my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof; and

FIG. 7 is a front, top and left side perspective view thereof.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 292,975
DATED : December 1, 1987
INVENTOR(S) : Fumiayuki Kobayashi

It is certified that error appears in the above-identified patent and that said Letters Patent is hereby corrected as shown below:

Change Figure 1 description to read as follows:
--FIG. 1 is a front elevational view of a combined carrying case and battery pack for a cordless telephone set, showing my new design;--

Signed and Sealed this
Fourteenth Day of March, 1989

Attest:

DONALD J. QUIGG
